CERTAIN NEW HETEROCYCLIC COMPOUNDS AND METHOD OF MAKING SAME

Verner L. Stromberg, Shrewsbury, Mo., assignor to Petroleum Corporation, Wilmington, Del., a corporation of Delaware

No Drawing. Application December 30, 1954,
Serial No. 478,933

10

10 Claims. (Cl. 260—211)

The present invention is concerned with certain new heterocyclic compounds and method of making same. Such compounds have utility in various arts, not only as such but after being converted into derivatives of the kind hereinafter described.

More specifically, the compounds derived are obtained by reaction involving a cyclic amidine having a terminal primary amino radical and a hydroxylated aldehyde of the kind exemplified by glucose.

In its simplest aspect the invention may be illustrated by a compound of the following structure:

Or the hydrogenated derivatives thereof, such as:

In the above structures the radical RC is the residual radical derived from a monocarboxy acid RCOOH. Such acid may have one carbon atom as in the case of formic acid or may have only 2 carbon atoms as in the case of acetic acid, or may have as many as 30 carbon atoms as in the case of a higher fatty acid.

The above formulas show the compounds derived from a substituted imidazoline, i. e., a five-membered ring compound but it is to be noted that comparable compounds having a six-membered ring are included. Such compounds instead of being derivatives of substituted imidazolines are derivatives of substituted tetrahydropyrimidines. Both types of cyclic compounds, of course, belong to the broader class of cyclic amidines.

The compounds above depicted are derivatives of triamine but one can use derivatives of higher alkylene amines such as triethylene tetramine, tetraethylene pentamine, etc. In such instances the secondary divalent amino radical, such as

would appear in the radical which links the heterocyclic ring with the hexose residue.

The type of compound herein depicted is not limited to monocarboxy acids, such as acetic acid and higher fatty acids, but includes dicarboxy acids such as di-glycolic acid, dimeric fatty acids obtained by the dimerization of unsaturated higher fatty acids such as linseed oil fatty acid, etc.

More specifically then the herein described amidines may be exemplified by the formula:

2

in which

5 has its previous significance, and R' is a member of the class consisting of

15 in which R'' is a radical selected from the class consisting of R'NH2 or

25 in which R has its prior significance and n is a small whole number. The amino cyclic amidine above depicted is combined with a hexose such as glucose.

If, however, the cyclic amidine is derived from a di-carboxy acid, such as HOOC-R1-COOH in which 30 R1 is the carboxyl-free dicarboxy acid residue, the di-cyclic amidine obtained would correspond to

35 in which the various characters have their prior significance.

40 In recapitulation then, the present invention is concerned with certain Schiff's Bases and hydrogenated derivatives thereof. The Schiff's Bases are obtained by reaction between:

(A) A member of the class consisting of:

45 (a) Substituted imidazolines and substituted tetrahydropyrimidines thereof, characterized by the presence of a terminal primary amino group, and

(b) Substituted diimidazolines and substituted ditetrahydropyrimidines, characterized by the presence of a 2 terminal primary amino group, and

50 (B) At least one mole of a hydroxylated aldehyde such as a hexose and particularly as exemplified by glucose.

In the case of the dicyclic compounds, reaction may involve one mole or 2 moles of glucose.

55 For convenience, what is said hereinafter will be divided into six parts:

Part 1 is concerned with suitable cyclic compounds containing a primary amino group in the terminal position. Part 1, for convenience, is divided into four divisions:

60 Division A is concerned with substituted imidazolines obtained from monocarboxy acids;

Division B is concerned with suitable substituted tetrahydropyrimidines obtained from monocarboxy acids;

65 Division C is concerned with substituted imidazolines obtained from dicarboxy acids;

Division D is concerned with substituted tetrahydro pyrimidines obtained from dicarboxy acids;

70 Part 2 is concerned with suitable hexoses or other polyols having a reactive aldehydic carbonyl group as exemplified by glucose;

Part 3 is concerned with the reaction involving the first two classes enumerated above;

Part 4 is concerned with hydrogenated derivatives of the compounds described in Part 3, preceding;

Part 5 is concerned with uses for the products obtained in Parts 3 and 4, preceding, and particularly those in which there is present a radical having at least 8 uninterrupted carbon atoms and preferably showing characteristic surface-active properties; and

Part 6 is concerned with derivatives obtained from the compounds described in Parts 3 and 4, preceding, in which such compounds serve as an intermediate for further reaction.

PART 1

The manufacture of cyclic amidines and particularly substituted imidazolines and substituted tetrahydropyrimidines, is well known. The production of such compounds has been described extensively in the patent literature and elsewhere. See Chemical Reviews, volume 54, No. 4, page 593. See also Imidazole and Its Derivatives, Part 1 (1953), Hoffmann.

Imidazolines are obtained in various ways including the preparation from imidazolines. For convenience, they will be referred to as dihydroimidazolines. Likewise, hexahydropyrimidines are readily obtainable from tetrahydropyrimidines.

Division A

Substituted imidazolines are obtained from a variety of acids beginning with the one-carbon acid (formic) through and including higher fatty acids or the equivalent having as many as 32 carbon atoms. Modified fatty acids also can be employed as, for example, phenyl stearic acid or the like. Cyclic acids may be employed, including naphthenic acids. A variety of other acids including benzoic acid, substituted benzoic acid, polycyclic acid, and the like, have been employed to furnish the residue RC from the acid RCOOH in which the C of the residue RC is part of the ring. The fatty acids employed for example, may be saturated or unsaturated. They may be hydroxylated or nonhydroxylated. Branched long chain fatty acids may be employed. See J. Am. Chem. Soc. 74, 2523 (1952). This applies also to the lower molecular weight acids as well.

It will be noted that a variety of substituted imidazolines are included in Table 1 following. In some instances there is a radical having 8 or more uninterrupted carbon atoms and in other instances this is not the case.

Actually, substituted imidazolines can be obtained from a variety of polyamines but only in the instance where one starts with a triamine or higher amine is there a residual group having a primary amino radical as herein required. This does not mean, however, that one could not start with ethylene diamine or with 1,2-propylene diamine. The cyclic compounds so obtained could be reacted with a mole of ethylene imine or propylene imine so as to introduce the terminal primary amino group. From a practical standpoint, however, the most readily available polyamines are diethylene triamine, triethylene tetramine, and tetraethylene pentamine. No particular advantage has been found in using other polyamines in which some other divalent radical, such as

appears. For this reason examples in Table 1 are limited to derivatives of the three most readily available polyamines above indicated.

5

TABLE 1

Ex. No.	RCOOH Sources of RC	R'
1a	Formic	CH ₂ CH ₂ NH ₂
2a	Propionic	CH ₂ CH ₂ NH ₂
3a	Isovaleric	CH ₂ CH ₂ NH ₂
4a	Stearic	CH ₂ CH ₂ NH ₂

25a	Phenylstearic	CH ₂ CH ₂ NHCH ₂ CH ₂ CH ₂ NH ₂
26a	Cresotinic	CH ₂ CH ₂ NHCH ₂ CH ₂ CH ₂ NH ₂
27a	Linoleic	CH ₂ CH ₂ NHCH ₂ CH ₂ CH ₂ NH ₂
28a	Salicylic	CH ₂ CH ₂ NHCH ₂ CH ₂ CH ₂ NH ₂
29a	2-Hydroxy-3-methoxybenzoic	CH ₂ CH ₂ NHCH ₂ CH ₂ CH ₂ NH ₂
30a	Naphthenic	CH ₂ CH ₂ NHCH ₂ CH ₂ CH ₂ NH ₂

40 The expression "detergent-forming acid" has been used a large number of times in various patents to characterize high molal monocarboxy acids having at least 8 and generally not over 32 carbon atoms. Such acids are composed of the elements carbon, hydrogen, and oxygen exclusively. Such acids are obviously characterized, as the name suggests, by the ability to combine with the usual water soluble bases such as caustic soda, caustic potash, ammonia and low molal water-soluble amines, to give water soluble products which are soaps having conventional detergative characteristics in hydrophile systems. They may be obtained not only from the higher fatty acids but also from petroleum sources. This class 45 is illustrated by naphthenic acids and acids obtained by the oxidation of petroleum hydrocarbons. Furthermore, 50 although resin acids such as abietic acid are ordinarily included in the instant invention these are eliminated from the standpoint of cyclic amidine production simply for the reason that ring formation apparently does not take place. They may form salts, however. The normal 55 variants of the fatty acids such as dihydroxy stearic acid and the like are included provided such addition or substitution product does not introduce any new element and provided the compound still has detergent-forming characteristics.

60

Division B

70 The only polyamine available on a large scale for the manufacture of tetrahydropyrimidines is 3,3'-iminobispropylamine. This product can be converted into the tetramine or pentamine by appropriate reaction with a suitable imine or by reaction with acrylonitrile, followed by the usual steps of converting the intermediate into the amine. Tetrahydropyrimidines comparable to the substituted amidines in Table 1, appear in Table 2 immediately following.

TABLE 2

Ex. No.	RCOOH Source of RC	R'
1b	Formic	CH ₂ CH ₂ CH ₂ NH ₂

22b	Undecylenic	CH ₂ CH ₂ CH ₂ NH ₂
23b	Linoleic	CH ₂ CH ₂ CH ₂ NH ₂
24b	Hydroxybutyric	CH ₂ CH ₂ CH ₂ NH ₂
25b	Methyloctadecanoic	CH ₂ CH ₂ CH ₂ NH ₂

Division C

The procedure employed in the manufacture of substituted imidazolines from dicarboxy acids, is comparable to that employed when monocarboxy acids are used as reactants. As in the case of the monocarboxy acids, the acid may introduce a radical having less than 8 uninterrupted carbon atoms or 8 or more uninterrupted carbon atoms.

Suitable products derived from the three amines previously noted are described in Table 3, following:

TABLE 3

Ex. No.	HOOC-R-COOH Source of -CRC-	R'

29c	Stearyl succinic	CH ₂ CH ₂ NH ₂
30c	Terephthalic	CH ₂ CH ₂ NH ₂

Division D

In the use of dicarboxy acids, the bulk of the examples were obtained from 3,3'-iminobispropylamine. These

compounds are comparable to those which appeared in Table 3, preceding.

PART 2

30 Suitable polyols having an aldehyde group which are reactive towards basic primary amines are well known. The preferred reactant is glucose. However, a number of additional reactants which may be included are the following: apiose, arabinose, erythrose, fucose, galactose, 35 glyceraldehyde, mannose, rhamnose, ribose, threose, and xylose.

PART 3

The two types of reactants previously described in 40 Parts 1 and 2, are combined under conventional conditions to produce a Schiff's Base compound. Generally the conditions require preferably a solvent in which both reactants are soluble, which allows the reaction to proceed at a lower temperature giving a lighter colored product. The reaction may be allowed to proceed in the absence 45 of solvent, however, eliminating the necessity of solvent removal from the viscous reaction product. This necessitates longer reaction times or higher temperatures being employed.

The procedure employed in obtaining the Schiff's Base 50 is illustrated by the following examples:

Example 1e

One mole of the imidazoline (1a, Table I) derived from formic acid was mixed with one mole of glucose. Stirring was continued overnight and the water formed 55 removed in vacuo. A light yellow product resulted.

Example 2e

One mole of the tetrahydropyrimidine (8b, Table 2) 60 derived from lauric acid was mixed with one mole of mannose and the resulting mixture heated. Water began to form, and could be removed, as the temperature became greater than 70° C. As heating continued the reaction became more vigorous until at 100° C. a spontaneous rise to 110° C. was noted. The heating was discontinued and the water formed removed in vacuo from the red brown viscous residue.

Example 3e

70 One mole of the diimidazoline (6c, Table 3) derived from diglycolic acid and one mole of arabinose were refluxed with a suitable quantity of methyl alcohol to ensure homogeneity for a period of three hours. The solvent and the water formed in the reaction were removed in vacuo giving a product characterized by the

presence of a free uncombined terminal primary amino radical.

Example 4e

One mole of the diimidazoline (13d, Table 4) derived from methylene disalicylic acid and two moles of ribose, were refluxed with a suitable quantity of isopropyl alcohol to ensure homogeneity for a period of three hours. The solvent and the water formed in the reaction were removed in *vacuo*, care being taken to reduce foaming. The product formed was a brown red viscous oil.

For sake of brevity, a number of other examples are included in Table 5 following. It will be noted in these examples, 1e to 20e, there are included a variety of compounds, some of which include a high molal radical, and some of which do not. In some instances the compounds contain a single heterocyclic ring and in some instances two heterocyclic rings. In some instances the rings are five-membered and in other instances six-membered. Some examples are characterized by the presence of a free uncombined terminal primary amino radical.

TABLE 5

Ex. No.	Cyclic Cmpd. Used	Moles	Aldehydic Compound Employed	Moles	Molal Ratio	Solvent	Temp., ° C.	Time, Hours

18e	7d	1	do	2	1:2	do	65	3
19e	16d	1	Glucose	1	1:1	Isopropanol	83	3
20e	18d	1	do	2	1:2	do	83	3

The above reaction is obtained by use of a hydroxylated aldehyde as specified. There are available a number of polyhydroxylated ketones such as dihydroxyacetone, erythrulose, fructose, sorbose, lactulose, and mannoheptulose, which may be used in the formation of Schiff's Bases. A ketone can be used to give a somewhat comparable class of material in which the hydrogen atom attached to the carbonyl carbon atom of the hydroxylated aldehyde is replaced by an organic radical. Such compounds which show the usual reactivity towards primary amino groups in forming a Schiff's Base, can be used in place of glucose or the other compound described in Part 2. However, this class of derivative although suitable for all reactions and processes herein described in regard to the compounds derived from aldehydes, is not included as part of the present invention.

PART 4

A variety of primary amines have been combined with glucose or the like to produce a compound comparable to the one herein described in that it is a Schiff's Base. Such compounds have been described in various patents such as:

U. S. Patent No. 1,985,424, dated December 25, 1934, to Piggott

U. S. Patent No. 2,016,962, dated October 8, 1935, to Flint et al.

U. S. Patent No. 2,016,963, dated October 8, 1935, to Flint et al.

U. S. Patent No. 2,193,433, dated March 12, 1940, to Salzberg

Using the same hydrogenation procedure in regard to the compounds described in Part 3, preceding, one can

readily convert the Schiff's Base into suitable amines which have certain advantages in instances over the Schiff's Base in that they have greater stability. It should be pointed out that when such reactants as described in Part 1, preceding, are subjected to hydrogenation if derived from an unsaturated fatty acid or unsaturated dicarboxy acid, the conversion to the corresponding saturated compound takes place almost without exception. Thus, the hydrogenated derivatives referred to in the appended claims include not only those in which the Schiff's Base has been converted into the corresponding amine but also those in which any unsaturated groups derived from mono- or dicarboxy acids have been converted into the corresponding saturated compound as noted above.

As a specific example illustrating the hydrogenation of the Schiff's Base obtained as previously described in Part 3, reference is made to the following three examples and 20 Table 6, following. It will be noted the procedure em-

ployed is substantially the one described in United States patents preceding.

Example 1f

100 grams of the Schiff's Base (Ex. 6e, Table 5) derived from glucose, triethylene tetramine, and salicyclic acid dissolved in 500 grams of water, and 10 grams of reduced nickel catalyst, containing 20% nickel supported on kieselguhr, was violently agitated under 2000 pounds hydrogen pressure at a temperature of 70° for 50 minutes. The catalyst was removed by filtration and the mother liquor concentrated, giving the reduced Schiff's Base as a viscous non-crystalline syrup.

Example 2f

100 grams of the Schiff's Base (Ex. 11e, Table 5) derived from mannose, 3,3'-iminobispropylamine and 2-hydroxy-3-methoxybenzoic acid dissolved in 700 grams of water and 10 grams of nickel catalyst was violently agitated under 2000 pounds hydrogen pressure at a temperature of 100° for 30 minutes. The catalyst was removed by filtration and the mother liquor concentrated, giving the product as a viscous non-crystalline syrup.

Example 3f

100 grams of the Schiff's Base (Ex. 15e, Table 5) derived from glucose, tetraethylengenetamine, and succinic acid dissolved in 500 grams of alcohol, and 10 grams of Raney nickel catalyst, was violently agitated under 100 pounds of hydrogen pressure at a temperature of 50° C., for 30 minutes. The catalyst was removed by filtration and the mother liquor concentrated, care being taken to reduce foaming, giving the reduced

diimidazoline Schiff's Base as a viscous non-crystalline syrup.

TABLE 6

Ex. No.	Cmpd. Hydrogenated	Grams	Catalyst	Temp., °C.	Pres., lbs. Sq. In.	Time, Mins.

The products described in Parts 3 and 4 may vary widely in regard to surface-active properties and particularly as far as solubility in water, or similar polar solvents go on the one hand and hydrocarbons, oils, or non-polar solvents on the other hand. A number of the products described and, in fact, all of them either before or after hydrogenation, have present one or more basic nitrogen atoms per molecule. Thus, they may be employed in the various forms in which comparable nitrogenous compounds are used, i. e., in the form of the anhydrous base, or in the form of the hydrated base (combination with water) or in the form of a salt. The salt may be a combination with an organic acid or an inorganic acid such as hydrochloric acid, phosphoric acid, nitric acid, sulfuric acid, etc., when derived from organic acids. The acid employed may be a carboxy acid or sulfonic acid. Furthermore, the acid may have more than one carboxyl group as in the case of diglycolic acid, tetracarboxybutane, etc.

When a salt is formed from a low molal organic acid, particularly a hydroxylated acid such as acetic acid, butyric acid, lactic acid, hydroxyacetic acid, gluconic acid, etc., the tendency is to increase the hydrophile properties. However, when a salt is derived from an organic acid having 8 or more carbon atoms, such as a higher fatty acid, naphthenic acid, abietic acid, or the like, the tendency is to decrease the hydrophile properties and increase the hydrophobe properties.

Any reference to the use of these acylation derivatives, as for example in the claims, specifically includes all the various forms including the salt form and the hydrated base form referred to above.

PART 5

In light of what has been said previously, it is obvious that the products as such and their salts, represent complete variation in hydrophobe-hydrophile balance from products which are extremely water-soluble to products which are essentially oil-soluble and have comparatively moderate hydrophile properties.

These products or compounds may be used for various purposes in the oil industry in which other cyclic amidines or cyclic amidine derivatives have been employed. Such uses include, among others, the following: Resolution of water-in-oil emulsions; resolution of oil-in-water emulsions; prevention of corrosion particularly of ferrous equipment; use in the acidization of calcareous structures; use in secondary oil recovery, etc.

As to the use of the herein described products in the same way that conventional demulsifying agents are employed, reference is made to U. S. Patent No. 2,626,929, dated January 27, 1953, to De Groote, and particularly to Part 3. Everything that appears therein applies with equal force and effect to the instant process, noting only that where reference is made to Example 13b in said text beginning in column 15 and ending in column 18, reference should be to Example 7e, herein described.

The new products herein described are useful as wetting, detergent and leveling agents in the laundry, textile

and dyeing industries; as wetting agents and detergents in the acid washing of building stone and brick; as wetting agents and spreaders in the application of asphalt in road building and the like; as a flotation reagent in the flotation separation of various aqueous suspensions containing negatively charged particles, such as sewage, coal washing waste water, and various trade wastes and the like; as germicides, insecticides, emulsifying agents as, for example, for cosmetics, spray oils, water-repellent textile finishes; as lubricants, etc.

So far as the use of the herein described products goes for the purpose of resolving petroleum emulsions of the water-in-oil type, and also for that matter for numerous other purposes where surface-active materials are effective, and particularly for those uses specified elsewhere herein, it is preferred to employ oxyalkylated derivatives which are obtained by the use of monoepoxides, in such manner that the derivatives so obtained have sufficient hydrophile character to meet at least the test set forth in U. S. Patent No. 2,499,368, dated March 7, 1950, to De Groote and Keiser. In said patent such test for emulsification using a water-insoluble solvent, generally xylene, is described as an index of surface activity.

The materials herein described, in many instances have a number of uses in the petroleum industry somewhat different from those previously described.

In the first place the material is valuable as a fuel oil additive in the manner described in U. S. Patent No. 2,553,183, dated May 15, 1951, to Caron et al. It can be used in substantially the same proportions or lower proportions and this is particularly true when used in conjunction with a glyoxalidine or amido glyoxalidine.

An analogous use in which these products are equally satisfactory, is that described in U. S. Patent No. 2,665,978, dated January 12, 1954, to Stayner et al. The amount employed is in the same proportion or lesser amounts than referred to in said aforementioned Caron et al patent.

The second use is for the purpose of inhibiting fogs in hydrocarbon products as described in U. S. Patents Nos. 2,550,981 and 2,550,982, both dated May 1, 1951, and both to Eberz. Here, again, it can be used in the same proportions as herein indicated or even small proportions.

A third use is to replace oil soluble petroleum sulfonates, so-called mahogany soaps, in the preparation of certain emulsions or soluble oils or emulsifiable lubricants where such mahogany soaps are employed. The cogeneric mixtures having this peculiar property, serve to replace all or a substantial part of the mahogany soap.

Another use is where the product does not serve as an emulsifying agent alone but serves as an adjunct.

Briefly stated, the fourth use is concerned with use as a coupling agent to be employed with an emulsifying agent. See "The Composition and Structure of Technical Emulsions," J. H. Goodey, Roy. Australian Chem. Inst. J. & Proc., vol. 16, 1949, pp. 47-75. As stated, in the summary of this article, states:

"The technical oil-in-water emulsion is regarded as a system of four components; the dispersion medium, consisting of the highly polar substance water; the disperse phase composed of hydrocarbons or other substances of comparatively weak polarity; the coupling agent, being an oil-soluble substance involving an hydroxyl, carboxyl or similar polar group; and the emulsifying agent, which is a water-soluble substance involving an hydrocarbon radical attached to an ionizable group."

Thus, these peculiar products, giving curdy precipitates with water, are unusually effective as coupling agents in many instances.

Fifth, these materials have particular utility in increasing the yield of an oil well by various procedures which in essence involve the use of fracturing of the strata by means of liquid pressure. A mixture of these products with oil or oil in combination with a gel former alone,

or a gel former and finely divided mineral particles, yields a product which, when it reaches crevices in the strata which are yielding water, form a gelatinous mass of curdy precipitate or solid or semi-solid emulsion of a high viscosity. In any event, it represents a rapid gelling agent for the strata crevices and permits pressure to be applied to fracture the strata without loss of fluid through crevices, openings or the like.

The herein described products and the derivatives thereof, are particularly valuable in flooding processes for recovery of oil from subterranean oil-bearing strata when employed in the manner described in U. S. Patent No. 2,233,381, dated February 25, 1941, to De Groot and Keiser.

The application of imidazolines as sold in the open market has been suggested for a variety of industries, such as the following:

Agriculture: kerosene, phenothiazine, pyrethrum sprays, fungicides, herbicidal oils.

Anti-static treatment: for hotel rugs, hospital floors, automobile upholstery, plastic and wax polishes, wool oils, lubricants for synthetic fibers.

Building materials: water repellent treatment for plaster, concrete, cement, roofing materials, air entrainment, floor sealers, linoleum.

Cosmetics: formulation of anti-perspirants, deodorants, sun screens, hair preparations.

De-emulsifying: in antibiotic extraction, breaking crude oil and water-gas for emulsions.

Detergents: metal cleaning emulsions, lens cleaners, floor oils, dry cleaning detergents, radiator flushes, cesspool acid, boiler scale solvents, germicidal corrosion-inhibited acid detergents for dairies, enamel equipment, toilet bowls.

Leather: flat liquoring oils, pickling, acid degreasing, dye fixative.

Metals: rust preventive oils, cutting oils, water displacing compounds, pickling inhibitor, solvent degreasing.

Paints: for improved adhesion of primers, preventing water spotting in lacquers, anti-skimming, pigment flushing, grinding and dispersing, anti-feathering in inks.

Petroleum: corrosion inhibitor and germicide in flood water treatment, de-emulsifying fuel oil additives, anti-strip agent in asphalt emulsions and cutbacks.

Textiles: in rubberizing, textile oils, dyeing assistants, softening agents.

Miscellaneous: bentonite-amine complexes, metal-amine complexes, preparation of pentachlorphenates, quaternaries, plastisols, and rodent repellents.

This new sub-genus of the broad class of cyclic amidines, is also effective for these same uses, part of which have been referred to previously.

PART 6

The products herein described may be combined with a variety of reactants as chemical intermediates, for instance, with various diepoxides or polyepoxides. They may be combined with a number of other monoepoxides, such as epichlorohydrin, styrene oxide, glycidyl and methylglycidyl. They may be reacted with alkyl glycidyl ether, glycidyl isopropyl ether, and glycidyl phenyl ether.

Furthermore, such products may be reacted with alkylene imines, such as ethylene imine or propylene imine, to produce cation-active materials. Instead of an imine, one may employ what is a somewhat equivalent material, to wit a dialkylaminoepoxypropane of the structure

wherein R' and R'' are alkyl groups.

The products may be combined with carboxy acids such as higher fatty acids so as to change their characteristics or with polycarboxy acids, such as diglycolic, maleic acid, phthalic acid, succinic acid, and the like, to give resins, soft polymers, or fractional esters which are essentially monomeric. Such products and others herein described, may all be used for the resolution of petroleum emulsions of the water-in-oil type. The products without further reaction are particularly valuable as additives for lubricating oils which are derived from sources other than petroleum.

Having thus described my invention, what I claim as new and desire to obtain by Letters Patent, is:

1. A chemical compound of the structure:

in which R is the carboxyl-free residue of an acid having not over 2 carboxyl radicals; R1 and R' are selected from the class consisting of:

50 R2(OH)n' is the aldehyde oxygen-free residue of a 3 to 6 carbon atom containing polyol having an aldehyde radical and reactive to primary amines; R3 is selected from the class consisting of H2 and R2(OH)n'; n is a small whole number including zero; n' is a small whole 55 number greater than one but not greater than five; n'' is a numeral not greater than one and including zero; and hydrogenated derivatives thereof.

2. A chemical compound of the structure:

75 in which R is the carboxyl-free residue of an acid having

not over 2 carboxyl radicals; R₁ and R' are selected from the class consisting of

R₂(OH)_{n'} is the aldehyde oxygen-free residue of a 3 to 6 carbon atom containing polyol having an aldehyde radical and reactive to primary amines; R₃ is selected from the class consisting of H₂ and R₂(OH)_{n'}; n is a small whole number including zero; n' is a small whole number greater than one but not greater than five; and n'' is a numeral not greater than one and including zero.

3. A chemical compound as defined in claim 2 with the proviso that R₁ and R' is the ethylene radical.

4. A chemical compound as defined in claim 2 with the proviso that R₁ and R' is the ethylene radical and n'' is zero.

5. A chemical compound as defined in claim 2 with the proviso that R₁ and R' is the ethylene radical, n'' is zero, and n is at least one and not greater than 2.

6. A chemical compound as defined in claim 2 with the proviso that R₁ and R' is the ethylene radical, n'' is zero, n is at least one and not greater than 2, and with the further proviso that the radical

is derived from a detergent-forming acid having at least 8 carbon atoms and not over 30 carbon atoms.

7. A chemical compound as defined in claim 2 with the proviso that R₁ and R' is the ethylene radical, n'' is zero, n is at least one and not greater than 2, with the further proviso that the radical

is the residue of a higher fatty acid having at least 8 carbon atoms and not over 22 carbon atoms.

8. A chemical compound as defined in claim 2 with the proviso that R₁ and R' is the ethylene radical, n'' is zero, 5 n is at least one and not greater than 2, with the further proviso that the radical

10 is the residue of a higher fatty acid having at least 8 carbon atoms and not over 22 carbon atoms in which R₂(OH)_{n'} is a glucose residue.

9. A chemical compound as defined in claim 2 with the proviso that R₁ and R' is the ethylene radical, n'' is 15 zero, n is at least one and greater than 2, with the further proviso that the radical

20 is the residue of a higher fatty acid having at least 10 carbon atoms and not over 20 carbon atoms in which R₂(OH)_{n'} is a glucose residue.

10. A chemical compound as defined in claim 2 with the proviso that R₁ and R' is the ethylene radical, n'' is 25 zero, n is at least one and greater than 2, with the further proviso that the radical

30 is the residue of a higher fatty acid having at least 12 carbon atoms and not over 18 carbon atoms in which R₂(OH)_{n'} is a glucose residue.
